PIE MAKING MACHINERY AND DIE

David Trompeter, Baldwin, N. Y., assignor to
Tri Pie Corporation, Brooklyn, N. Y., a corpora-
tion of Delaware

Application October 1, 1931, Serial No. 566,226

4 Claims. (Cl. 107—1)

This invention relates to pie making machinery and dies therefor and more particularly to a machine for converting one large raw pie into a plurality of individual sector shaped pies each 5 having the cubicle contents of the conventional sector shaped pie portion.

One object of this invention is a machine for making die stamped or die molded pies.

Another object of this invention is a die for 10 use in said machine.

Another object of this invention is to insure the sealing of the individual sector shaped pies in the operation of sub-dividing the large pie.

In the drawings comprising three sheets of thir- 15 teen figures numbered Figs. 1 to 13 inclusive one embodiment of the invention is set forth.

Fig. 1 is a side view of the complete machine or press;

Fig. 2 is a horizontal sectional view taken along 20 the line 2—2 of Fig. 1, looking in the direction of the arrows;

Fig. 3 is a plan view of the pie plate constituting the female member of the die looking down- 25 ward from above as indicated by the arrows and the line 3—3 of Fig. 1;

Figure 4 is a plan view of the top of the press with certain of the parts in section, taken along the line 4—4 of Fig. 1, looking in the direction of the arrows;

Fig. 5 is an enlarged side view of the male die and rimmer and a vertical sectional view of the female die member with a pie partially formed therein;

Fig. 6 is a vertical section of the device of 35 Fig. 5 with its several parts co-acting to complete the pie;

Fig. 7 is a plan view of the male die of Fig. 5, looking upwards from beneath the die in said figure;

Fig. 8 is a vertical sectional view of the rimmer and female die after the pie rimming operation is completed;

Fig. 9 is a vertical sectional view taken along the line 9—9 of Fig. 6 looking in the direction of 45 the arrows;

Fig. 10 is a vertical section of an alternative form of male and female die combination, showing a vertical section of the female die of Fig. 11, taken along the line 10—10 of the latter figure 50 looking in the direction of the arrows;

Fig. 11 is a plan view of the female die or pie pan of Fig. 10;

Fig. 12 is a perspective view of an individual sealed sector shaped pie, die molded by the ma- 55 chine or press of Fig. 1, and

Fig. 13 is a vertical section of the pie of Fig. 12.

Like reference characters designate corre- 60 sponding parts throughout the several figures of the drawings.

Referring to Fig. 1, the device includes a bench or table 21 supported by legs 22, reinforced by the cross brace 41. A metal frame 20, secured to the bench 21 in any preferred manner, supports the male die. The table top is provided 65 with a series of intersecting rib-like members 39, which are adapted to engage in the channels formed in the underside of the pie plate 38 (or 53—Fig. 11) to center the plate relative to its complementary male die, to permit the latter in 70 descending to register with the pie plate, which then functions as a female die, where in the molded pie is completely formed and sub-divided. The shaft 24 is slidably supported in the holder 75 23 of the frame 20, the shaft 24 being grooved and holder 23 having a spline 60 as indicated in dotted lines in Fig. 1, to key the holder to the shaft to permit vertical sliding movement while at the same time preventing rotary move- 80 ment between said shaft 24 and holder 23. Shaft 24 is slotted near its upper end to receive a pair of rollers 25—25 rotatably mounted in said slot. Lever arm 29 which is pivoted to frame 20 as at 85 28 extends through the slot in shaft 24 and controls the downward sliding movement of said shaft against the increasing tension of coiled spring 27 which stores energy as collar 26 secured to shaft 24 approaches the holder 23 in the downward 90 sliding movement of said shaft. A foot actuated lever 40, is pivotally mounted at 42 to the cross brace 41, and levers 40 and 29 are pivotally connected together by means of the rod 30, so that whenever the former is depressed by foot pres- 95 sure, rod 30 moves upwards and lever 29 trans- 100 mits the swinging movement of lever 40 to shaft 24 which translates the same into a downward thrust to carry the male die 35 and rimmer 31 towards the female die 38 supported on the bench 21.

The male die 35 is secured in any preferred manner to a hub 37 which is in turn secured to shaft 24, said die being locked to said shaft against rotary movement. Hub 36 is rotatably mounted upon the shaft 24, and rimmer 31 is connected to hub 36 by means of the supports 32 carried 105 by the radial arms 33 which are screwed into hub 36. Handle 34 facilitates the rotary move- 110 ment of hub 36 and consequently of rimmer 31.

The pie plate or mold 38 (Fig. 3) is sub-divided into a plurality of sector shaped receptacles 43

wherein the sector shaped pies are intended to be formed (compare Figs. 3, 5, 6, 10 and 11).

The upper or male die 35 consists of an annular flange having a series of radially extending flanges sub-dividing the die into a series of sector shaped walled areas equal in number to the number of receptacles in molds 38 and 53 (Figs. 3 and 11). These flanges co-act with the corresponding flanges of either mold to compress the 10 layers of dough therebetween (see Figs. 6, 8, 9 and 10). The annular and radially extending flanges may be serrated as indicated at 44 (Figs. 5, 6 and 7) in which event the peripheral marginal edges of the sector shaped pies will when finished 15 have an undulatory crimped appearance more nearly simulating the appearance of a home made pie somewhat as shown in Fig. 12. A series of cutters 45 are affixed along the middle of the flanges of the male die 35. These cutters project 20 below the flange as indicated in Figs. 5 and 6, and serve to sever the upper and lower layers of pie 46 and 48 along the middle line of the flanges of the lower mold (indicated by beads 54 of mold 53—Fig. 11) to sub-divide the large pie with waste 25 age into a plurality of individual sector shaped pies equal in number to the number of spaced receptacles.

The rimmer 31 as shown is an annular cutter for trimming off the excess dough overhanging 30 the edge of the pie plate (see Fig. 5), to produce the trimmed edge of Fig. 6, 8, 9 or 10.

In order to understand the principle of operation it may be advisable to consider Figs. 3, 5 and 13 together. A large sheet of dough 46 is first 35 placed upon the pie plate 38 to overhang the edge thereof and is then lined against the walls of the several receptacles by means for example of a matrix consisting of a series of sector shaped projections each conforming in configuration to 40 the configuration of the inner walls of the receptacles 43 of the plate 38 or receptacles 55 of plate 53. One suitable form of matrix for this purpose is disclosed in my Patent Number 1,841,507, granted January 19, 1932. The sweetmeat 47 is now 45 placed in the dough lined receptacles which are then completely covered by the upper sheet of dough 48. The raw unfinished pie now resembles in general appearance the pie shown in Fig. 5. The pie plate 38 is now centered on the bench 50 21 relative to the male die 35 by means of the intersecting ribs 39 engaging the channels formed in the underside of the pie plate 38. Lever 40 is now operated and male die 35 moves downwards followed by rimmer 31, until the pie pan 38 55 (which in effect now constitutes a complementary female die), male die 35, and rimmer 31, assume the position indicated in Fig. 6, in which condition the dough overhanging the edge of plate 38 as shown in Fig. 5 is trimmed off and removed by 60 the rimmer 31; cutters 45 of male die 35 (Fig. 7) separate the large pie along the radial partitioning walls of the pie plate 38 (or 53—Fig. 1); and the flanges 44 of the radial and peripheral walls of male die 35 engage and compress the upper 65 and lower layers of dough 48 and 46 throughout their entire periphery to crimp the entire peripheral marginal edge of each individual sector shaped pie so as to completely seal the sweetmeat 47 of each individual pie in a shell like 70 housing of dough.

The undulations 44 more nearly simulate in appearance the crust of the home made crimped pie, as is illustrated in Fig. 12; but these undulations 44 may be omitted from the male die 75 35 if preferred.

The pie may if preferred be so formed that the upper layer of dough 48 will be convex as best indicated by the cross section of Fig. 13.

The rimmer 31 is bevelled so that its sharp lower edge is of larger diameter than the pie 80 pan 38, but as the width of the rimmer 31 increases its internal diameter decreases until at the top the rimmer is preferably of smaller diameter than the pie pan 38, so that the trimming of the waste dough is assured without permitting the sharp edge of rimmer 31 to engage on the top of pie pan 38 or upon the bench top 21. The varying internal diameter of rimmer 31 allows for commercial variations in the diameter of the pie pans 38, as the rimmer must 90 be designed to operate with pie pans having such commercial variations of diameter.

The rimmer 31 may be rotated during or after its descent by the manual operation of handle 95 34 whereby the rimmer is caused to turn with its hub 36 relative to shaft 24, the bevelled wall of rimmer 31 operating to smooth out the trimmed edge of the layers of dough 46 and 48 thereby still further tending to obliterate any appearance of separate layers of dough. 100

The male die 50 (Fig. 10) is similar to male die 35 (Fig. 6) but does not include the serrations 44 (see Fig. 7). The radial partition walls 52 of male die 50 are united at the center to a hub 51 upon which the die may be securely 105 mounted upon the shaft 24.

What is claimed is:

1. In a pie finishing machine and in combination, a male die member having a downwardly extending wall encircling the die, a series of 110 equally spaced partition walls forming inwardly projecting radial extensions of said annular wall and joined together at the centre, said annular and partition walls in conjunction thereby defining a plurality of sector shaped walled areas 115 each substantially equal in area to a standard sector shaped individual pie portion, the faces of all of said walls lying in the same horizontal plane to constitute means operable to compress the dough, a series of cutters equal in number to the 120 number of partition walls and secured to and along the centre lines of the faces thereof and projecting therebeyond to the outer edge of the face of the annular wall, to define a plurality of open V shaped cutting members equal in number 125 to the number of sector shaped receptacles having their cutting edges lying in the same horizontal plane, a rimmer encircling and rotatably mounted relative to the die encircling wall, a multi-unit pie plate for containing one large pie 130 said plate forming one of a series of interchangeable female dies complementary to said male die, and being sub-divided into a plurality of spaced receptacles each receptacle being triangular or sector shaped and having a bottom wall, side 135 walls constituting partition walls between adjacent receptacles, and a back wall, adjacent partition walls converging so that their upper edges define V shaped seats operable when said dies are brought into co-operative registry to co-act 140 with the open V shaped cutters of the male die to sub-divide the large pie into a plurality of individual pies equal in number to the number of spaced receptacles, and the partition and back walls in conjunction defining triangular or sector 145 shaped seats operable when said dies are brought into co-operative registry to co-act with the triangular or sector shaped dough compressing means of the male die to horizontally compress the upper and lower marginal edges of said individual pie. 150

- vidual pies throughout the entire periphery of each of them in the operation of forming the same, and means for bringing said male and female dies into cooperative registry to effect said sub-dividing and compressing operations.

2. In a pie finishing machine and in combination, a male die member having a downwardly extending wall encircling the die, a series of equally spaced partition walls forming inwardly projecting radial extensions of said annular wall and joined together at the centre, said annular and partition walls in conjunction thereby defining a plurality of sector shaped walled areas each substantially equal in area to a standard sector shaped individual pie portion, the faces of all of said walls lying in the same horizontal plane to constitute means operable to compress the dough, a series of cutters equal in number to the number of partition walls and secured to and along the centre lines of the faces thereof and projecting therebeyond to the outer edge of the face of the annular wall, to define a plurality of open V shaped cutting members equal in number to the number of sector shaped receptacles having their cutting edges lying in the same horizontal plane, a rimmer encircling and slidably mounted relative to the die encircling wall, and a multi-unit pie plate for containing one large pie said plate forming one of a series of interchangeable female dies complementary to said male die, and being sub-divided into a plurality of spaced receptacles each receptacle being triangular or sector shaped and having a bottom wall, side walls constituting partition walls between adjacent receptacles, and a back wall, adjacent partition walls converging so that their upper edges define V shaped seats operable when said dies are brought into cooperative registry to co-act with the open V shaped cutters of the male die to sub-divide the large pie into a plurality of individual pies equal in number to the number of spaced receptacles, and the partition and back walls in conjunction defining triangular or sector shaped dough compressing means of the male die to horizontally compress the upper and lower marginal edges of said individual pies throughout the entire periphery of each of them in the operation of forming the same, and means for bringing said male and female dies into cooperative registry to effect said sub-dividing and compressing operations.

4. In a pie finishing machine and in combination, a holder, a shaft slidably keyed in said holder, a male die member mounted on said shaft, said die having a downwardly extending wall for encircling the die, a series of equally spaced partition walls forming inwardly projecting radial extensions of said annular wall and joined together at the centre, said annular and partition walls in conjunction thereby defining a plurality of sector shaped walled areas each substantially equal in area to a standard sector shaped individual pie portion, the faces of all of said walls lying in the same horizontal plane to constitute means operable to compress the dough, a series of cutters equal in number to the number of partition walls and secured to and along the centre lines of the faces thereof and projecting therebeyond to the outer edge of the face of the annular wall, to define a plurality of open V shaped cutting members equal in number to the number of sector shaped receptacles having their cutting edges lying in the same horizontal plane, a die encircling rimmer independently mounted on said shaft and slidably and rotatably relative to said die, and a multi-unit pie plate for containing one large pie said plate forming one of a series of interchangeable female dies complementary to said male die, and being sub-divided into a plurality of spaced receptacles each receptacle being triangular or sector shaped and having a bottom wall, side walls constituting partition walls between adjacent receptacles, and a back wall, adjacent partition walls converging so that their upper edges define V shaped seats operable when said dies are brought into cooperative registry to co-act with the open V shaped cutters of the male die to sub-divide the large pie into a plurality of individual pies equal in number to the number of spaced receptacles, and the partition and back walls in conjunction defining triangular or sector shaped dough compressing means of the male die to horizontally compress the upper and lower marginal edges of said individual pies throughout the entire periphery of each of them in the operation of forming the same.

3. In a pie finishing machine and in combination, a male die member having a downwardly extending wall encircling the die, a series of equally spaced partition walls forming inwardly projecting radial extensions of said annular wall and joined together at the centre, said annular and partition walls in conjunction thereby defining a plurality of sector shaped walled areas each substantially equal in area to a standard sector shaped individual pie portion, the faces of all of said walls lying in the same horizontal plane to constitute means operable to compress the dough, a series of cutters equal in number to the number of partition walls and secured to and along the centre lines of the faces thereof and projecting therebeyond to the outer edge of the face of the annular wall, to define a plurality of open V shaped cutting members equal in number to the number of sector shaped receptacles having their cutting edges lying in the same horizontal plane, a rimmer encircling the wall of the die and slidably and rotatably mounted relative thereto, a multi-unit pie plate for containing one large pie said plate forming one of a series of interchangeable female dies complementary to said male die, and being sub-divided into a plurality of spaced receptacles each receptacle being triangular or sector shaped and having a bottom wall, side walls constituting partition walls between adjacent receptacles, and a back wall, adjacent partition walls converging so that their upper edges define V shaped seats operable when said dies are brought into cooperative registry to co-act with the open V shaped cutters of the male die to sub-divide the large pie into a plurality of individual pies equal in number to the number of spaced receptacles, and the partition and back walls in conjunction defining triangular or sector shaped dough compressing means of the male die to horizontally compress the upper and lower marginal edges of said individual pies throughout the entire periphery of each of them in the operation of forming the same.

DAVID TROMPETER.
